1,936,252

ELECTRODE FOR ELECTROLYTIC DEVICES

Frederick W. McNamara, North Adams, Mass.,
assignor to Sprague Specialties Company,
Quincy, Mass., a corporation of Massachusetts

Application August 15, 1930. Serial No. 475,591

9 Claims. (Cl. 175—315)

My invention relates to a novel construction of anodes for use in electrolytic condensers and similar devices.

As is well known, an electrolytic condenser consists of an anode of film-forming metal, partially immersed in a suitable electrolyte and connected outside of the electrolyte to suitable terminals. The cathode which is either of film-forming or non-film-forming material forms the container 10 for the electrolyte.

The electrolytic condenser is characterized by the fact that when an electric current is passed through it, a film is built up on the part of the anode immersed in the electrolyte, which film 15 possesses high dielectric capacity and high insulating properties, permitting only a very slight current to pass from the anode toward the cathode. The dielectric capacity of such a condenser is directly proportional to the area of the anode 20 covered by the film and thus directly proportional to the area of the anode immersed in the electrolyte. To obtain high capacity in a small volume it is therefore desirable to have this part of the anode with as large surface as possible.

25 The passage of current through the condenser, however causes oxygen to be liberated at the anode, which attacks the anode at the gas-electrolyte inter-face. If the anode be constructed of thin sheet the result of this attack is that the 30 anode becomes weakened and in a short time fails mechanically.

The products of the attack, moreover, are substances which normally foul the electrolyte. To insure a minimum of corrosion, the anode, at the 35 point of projection from the electrolyte should be of as small surface as possible; and at the same time to insure strength, should be as substantial as possible.

A desirable anode is then one which combines 40 the qualities of being of small surface at the point of projection from the electrolyte and of large surface where it is immersed in the electrolyte. In the prior art such construction has been attempted by making the anode of two 45 pieces, one of which, a narrow stem, projects from the electrolyte and the other, consisting of rolled or crimped foil, is totally immersed in the electrolyte. The two pieces are joined together at points which after assembly are immersed in the 50 electrolyte. This joining is habitually performed by riveting, welding, a combination of the two or other well-known means. Such construction is costly, involving as it does a multiplicity of operations. It is furthermore characteristic of such 55 construction that adjacent to the joining points

or contacts are found seams, cracks, crevices and the like. In an electrolytic condenser incorporating such an anode the electrolyte has no free access to these seams and cracks and accumulation of gas retards or prevents altogether the formation of the film at such places. Thus, the film formed on the anode will be irregular and of uncertain properties in the neighborhood of these seams and cracks. These places are characterized by low insulating resistance and increase the 60 leakage current of the condenser. Furthermore, when such a condenser is in operation, slight vibration or other motion may disturb the accumulated gas, exposing a fresh anode surface to electric current. This may result in a possible short 65 circuiting of the condenser.

The prior types of anodes also suffer from the fact that the ratio of edges to surfaces is unnecessarily high. To build a smooth film it is necessary to have on the anode a fairly smooth metal 70 surface. This necessary smoothness is not to be obtained at a sharp edge or point and consequently poor films are formed in these regions. It is, moreover, characteristic of dielectrics such as these films are, that when charged, the charge 75 tends to be concentrated in the sharp edges or points. So that when anodes are constructed with sharp-edged foil a high concentration of charge accumulates in these edges which frequently results in flashovers, high leakage and the 80 like.

Anodes which eliminate all of these difficulties have been proposed in the co-pending application, Ser. No. 416,939 filed December 27, 1929, of F. Desmond Sprague and R. U. Clark, such anodes 85 consisting of a thin walled corrugated tube provided with a narrow supporting neck.

In a preferred embodiment of such anodes as also shown in the co-pending application Ser. No. 441,128 filed April 2, 1930, of Max Knab, the tube 90 is provided with helical corrugations. The area of such anodes and thus the capacity of the condenser depends on the mean diameter of the tube, the number of threads per inch and the depth of the thread. As the number of the depth of the 100 threads cannot be increased beyond certain limits, when such limits have been reached, the capacity of the condenser can only be increased by increasing the diameter of the tube.

To further increase the capacity of the condenser for a given container without sacrificing the advantages obtained with the above described anodes, I have devised a multiple-piece anode consisting of a plurality of concentric corrugated tubes of different diameters, each provided with 110

supporting necks whereby the supporting necks of the smaller tubes are inserted in the supporting necks of the tubes of larger diameter.

The mechanical and electrical contact between the individual supporting necks is so intimate over their whole contacting areas, that the possibility of crevices, cracks and the like as well as the introduction of electrical contact resistance is altogether eliminated.

10 The object of my invention is therefore to provide a multiple piece anode for electrolytic devices consisting of concentric corrugated tubes.

15 A further object of my invention is to provide a perfect mechanical and electrical contact between the individual pieces of the anode.

20 A further object of my invention is to provide such a mechanical and electrical connection, by means of cooperating extensions of the individual pieces, these extensions projecting from the electrolyte.

25 Further objects of my invention will appear as this specification progresses.

Referring now to the drawing, which forms part of this specification, the figure is a side elevation, partly in section and with parts broken away, showing an electrolytic condenser embodying my invention. The condenser comprises a container 20, which may be of film-forming or non-film-forming material and an anode which consists of an outer piece 1 and an inner piece 2. The outer piece 1 comprises two portions viz, a hollow supporting neck 3 and integral therewith a thin walled tubular portion 4, the two portions 3 and 4 being inter-connected by a conical portion 5 provided with circulating holes 6. The free end 7 of the supporting neck 3 is bevelled.

30 The tubular portion 4 is preferably provided with closely spaced flat helical corrugations, although other types of corrugations may be provided or even a smooth tubular portion used.

35 The inner piece 2 consists of a tubular portion 8 and a slightly tapered supporting neck 10, the tube 8 and neck 10 being connected by means of a conical portion 9; the portion 9 is provided with circulating holes 9a. The tube 8 which is of smaller diameter than the tube 4 is concentrically located within the latter, whereby the supporting neck 10 is surrounded by and projecting through the supporting neck 3. The free end 50 of the neck 10 is threaded at 11 and is provided with nuts 12—12' to form the outside of the anode.

45 The tubular portion 8 is preferably provided with closely spaced flat helical corrugations, although other types of corrugations may be provided or even a smooth tubular portion used.

50 A suitable electrolyte 13 is provided in the container, which fully covers the conical portion 5 of the outer tube.

55 The container 1 is provided with a cover 14 of insulating material which rests in an annular indentation 15 of the container and which by means of the lower nut 12' supports the anodes 1 and 2. On its top, the cover is provided with a peripheral recess in which rests a rubber gasket 17 over which the free end of the container is crimped for the proper sealing of the device. Sealing means (not shown) also may be provided between the cover 14 and the neck 10 of the anode.

70 A rubber vent 18 with a pin hole 19 provides for the escape of the gases.

75 To prevent corrosion between the two pieces of the anode as well as other objectionable effects, for instance undue contact resistance and thus

maintain the advantages of a one-piece anode of the type disclosed in the above applications, special care is to be taken to insure perfect electrical and mechanical connection between the two pieces 1 and 2 of the anode. This, I have obtained by providing a forced fit between the supporting necks 10 and 3.

80 While I have described and illustrated an anode consisting of only two pieces, it is well understood that such anodes may comprise a larger number of pieces similarly arranged. It is also feasible without departing from the spirit of my invention to arrange the tubular portions or the neck portions asymmetrically instead of concentrically.

85 It should be also well understood that while I have described a specific construction of the anode and illustrated such in a special application, I do not wish to be limited to such construction or application, but desire the appended claims to be construed as broadly as permissible in view of the prior art.

90 What I therefore claim as new and desire to secure by Letters Patent is:

1. An anode for electrolytic condensers comprising a plurality of pieces located within each other, each piece having two integral portions, one being a thin walled tubular portion having crimps in planes substantially perpendicular to the axis of the tube, the other portion being of substantial thickness and of small surface, the portions of small surface of the individual pieces being in intimate electrical and mechanical contact with each other.

100 2. In an electrolytic device, a container, an electrolyte and an anode comprising a plurality of substantially concentric pieces, each piece having a portion forming a corrugated tube of closely spaced flat helical corrugations submerged in the electrolyte and a portion emerging from the electrolyte, said emerging portions of the individual pieces forming an intimate electrical and mechanical contact with each other.

110 3. In an electrolytic condenser, a container, an electrolyte and a multiple piece electrode, each piece of said electrode comprising a tubular corrugated portion immersed in the electrolyte and a co-axial portion extending from the electrolyte, the portions extending from the electrolyte of the individual pieces being in direct and intimate electrical and mechanical connection with each other.

120 4. In an electrolytic condenser, a cylindrical container forming one electrode of the condenser and a second electrode comprising tubular members mechanically and electrically connected with each other, said members being disposed substantially co-axial with said container and having neck portions surrounding each other.

130 5. An electrode for electrolytic devices comprising a tubular member provided with an attenuated neck and a second tubular member disposed within said first member and having a portion snugly fitting in said attenuated neck and projecting therethrough, to form an outside connection for the electrode.

135 6. In an electrolytic device comprising a container forming one electrode, a cover of insulating material, a second electrode comprising a plurality of individual members co-axially disposed within said container, one of said members projecting through said cover to form an outside terminal for said electrode and a second of said members intimately surrounding said first member.

7. An anode for electrolytic condensers comprising a plurality of substantially co-axial members, each member having integrally a portion of small effective area and of substantial thickness and a portion of large effective area and of lesser thickness, the portions of small effective area of the two members forming interlocking cylindrical portions which are in intimate electrical and mechanical contact with each other. 10
8. An anode for electrolytic condensers, comprising a plurality of substantially co-axial members, each member having two integral portions, one forming the effective electrode and the other connecting said electrode to an outside terminal, the latter portions of the individual members surrounding each other and being in direct and intimate electrical and mechanical contact with each other. 20
9. An electrode for electrolytic condensers comprising a tubular member having an attenuated neck, and a second tubular member disposed within said first member and being with said neck in intimate electrical connection. 30
